Abstract: The present invention relates to a device for applying pressure to a lens blank in a surface grinding or polishing machine. It is an object of the present invention to provide a device which will hold a lens blank in a position such that the lens blank will be held in contact with a lap, and which will apply pressure to the lens blank from a point which lies in a plane below the lens blank.

LENS GRINDING MACHINE

Joseph S. Galeski, Richmond, Va.

Application August 31, 1932, Serial No. 631,212

4 Claims. (Cl. 51—129)

This invention relates to abrading machines and more particularly it has reference to machines which are used for grinding and polishing lenses.

One of the objects of my invention is to provide an improved device for grinding and polishing lenses having convex surfaces whose radii of curvature are relatively short. Another object is to provide means for grinding and polishing lenses in which the pressure for urging the lens and lap into contact is applied at or slightly below the surface of the lens. These and other objects and advantages reside in certain novel features of construction, arrangement and combination of parts as will hereinafter be more fully described and pointed out in the appended claims.

Referring to the drawing:

Fig. 1 shows my device in operation.

Fig. 2 is a front elevation of my device.

Fig. 3 is a side view of my device.

Fig. 4 is a top plan view of same.

Fig. 5 is a sectional view illustrating the use of my device.

In the usual practice of grinding and polishing spherical lenses in prescription shops, a single lens blank is attached to a lens block by a suitable adhesive such as pitch. A lap having the proper curvature is placed on a rotatable spindle 30 and the lens blank is then held firmly down against the rotating lap. A suitable grinding or polishing compound, such as emery or rouge, is, of course, applied to the lap.

In grinding or polishing a spherical convex or plus lens having a curvature with a short radius considerable difficulty is encountered. This is due to the fact that with such a strongly curved convex surface the point of application of the pressure is relatively high above the lens surface.

This puts the lens in a condition of unstable equilibrium so that when pressure is applied there is a great tendency to tip the lens with the result that the lens is often chipped or shattered. Such a tipping of the lens in polishing causes the outer zones of the lens to be completely polished long before the central portion is completely polished.

To overcome these difficulties I have provided a device whereby the effective pressure is applied to the lens block from a plane which is substantially at or below the surface of the strongly curved plus lens. My device, indicated generally at 15, and illustrated on Figs. 1 to 5 of the drawing, comprises a substantially rectangular ring member 16 to which are pivotally mounted, by

pins 17, the two depending arms 18 and 18' of the yoke 19. Secured to the yoke 19 is a member 20 within which a bushing 21 is mounted to turn on the ball bearing 21'. The projection 22 of a lens block 23, carrying lens blank L, is mounted in bushing 21 so that the blank may rotate freely. Mounted above and substantially at right angles to yoke 19 is the second yoke 24 having two depending arms 25 which are pivotally connected to ring 16 by pins 26. Mounted on top of yoke 24 is a bearing cup member 27 within which the pin 14' on lever 12, pivoted at 13 is adapted to be positioned.

Fig. 1 shows the use of my device in connection with the usual surfacing machine. The pin 14' on lever 12 projects into the bearing cup 27 and is rigidly secured thereto by set screw 27'. It will thus be apparent that pressure can be transmitted from the lever 12 through the yoke 24 to the ring member 16 and thence through yoke 19 to the lens block 23. The device 15 is held against rotation though the lens blank L may rotate freely on ball bearing 21'. Pressure is thus applied to the lens block from a plane which is substantially at or slightly below the surface of the lens being operated upon. This affords greater stability and so reduces the tipping tendency of the lens.

From the foregoing it will be apparent that I am able to attain the objects of my invention and provide an improved device for use in surfacing strongly curved convex lenses. Although I have illustrated my device as applied to a surfacing machine for producing spherical convex lenses, it can be equally well applied to surfacing machines which are used to produce convex toric lenses, as will be understood by those skilled in the art. Various modifications can obviously be made without departing from the spirit of my invention.

I claim:

1. In a lens grinding and polishing machine the combination of a lap, a member adjacent to the lap and arm extending upwardly from said member, a lens block rotatably mounted on said arm, said block carrying a lens to be operated upon and means for applying pressure to said member at a point which lies in a plane below the lens so as to urge said lens and lap into contact with each other.

2. In a lens grinding and polishing machine the combination of a ring member, a yoke having two downwardly projecting arms pivotally connected to said ring member, a lens block carried by said yoke, a second yoke positioned above and

- substantially at right angles to said first named yoke, said second yoke having downwardly extending arms pivotally secured to said ring member, and a bearing cup carried by the second yoke.
- 5 3. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 15
4. A device of the character described comprising a rotatable spindle carrying a lap, a lens block carrying a lens to be operated upon, a yoke having two arms pivotally secured to a ring member, a second yoke positioned above said first named yoke, said second yoke having two arms pivotally mounted to said ring member, said lens block being carried by said first named yoke and means for selectively applying pressure to the second yoke.

- JOSEPH S. GALESKI.
- 90
16. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 95
17. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 100
18. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 105
19. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 110
20. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 115
21. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 120
22. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 125
23. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 130
24. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 135
25. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 140
26. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.
- 145
27. A device for grinding and polishing lenses comprising a spindle carrying a lap, a member surrounding said lap, an arm carried by and extending upwardly from said member, a lens block mounted on said arm, said block carrying a lens 10 to be operated upon by said lap and means for applying pressure solely to said member whereby the pressure is transmitted to said block and the lens urged into contact with the lap.

CERTIFICATE OF CORRECTION.

Patent No. 1,974,607.

September 25, 1934.

JOSEPH S. GALESKI.

It is hereby certified that error appears in the printed specification of the above numbered patent requiring correction as follows: Page 1, line 99, claim 1, strike out the word "and" and insert instead the comma and word , an; and that the said Letters Patent should be read with this correction therein that the same may conform to the record of the case in the Patent Office.

Signed and sealed this 16th day of October, A. D. 1934.
